UNITED STATES PATENT OFFICE.

EDGAR F. HATHAWAY, OF WELLESLEY, AND WALTER BIXBY, OF DORCHESTER, MASSACHUSETTS, ASSIGNEES TO SHAWMUT ENGINEERING COMPANY, OF DORCHESTER, MASSACHUSETTS, A CORPORATION OF MASSACHUSETTS.

MECHANISM FOR PLACING TUFT YARNS IN CARPET MANUFACTURE.

Application filed March 14, 1922. Serial No. 543,589.

To all whom it may concern:

Be it known that we, EDGAR F. HATHAWAY and WALTER BIXBY, citizens of the United States, and residents, respectively, of Wellesley, in the county of Norfolk, and Dorchester, in the county of Suffolk, and State of Massachusetts, have invented an Improvement in Mechanism for Placing Tuft Yarns in Carpet Manufacture, of which the following description, in connection with the accompanying drawings is a specification, like characters on the drawings representing like parts.

This invention relates to mechanism for placing tuft yarns in carpet manufacture through the tubes of a tube frame, such as employed in the manufacture of Axminster or similar carpets or rugs, and particularly includes improved means for placing the tuft yarns used in weaving such rugs in the separate tubes of the tube frame or pile thread guide employed in such looms.

In order that the principle of the invention may be readily understood, we have disclosed a single embodiment thereof in the accompanying drawings, wherein—

Fig. 1 is a plan view of the left hand end of the machine constituting the disclosed embodiment of the invention;

Fig. 2 is a plan view of the right hand end thereof;

Fig. 3 is a front elevation of the end of the mechanism shown in Fig. 1;

Fig. 4 is a front elevation of that end of the mechanism shown in Fig. 2;

Fig. 5 is an end elevation of the drive end of the mechanism;

Fig. 6 is a central sectional elevation upon the line 6—6 of Fig. 1;

Figs. 7 and 8 are views of the comb holder having the comb inserted with the teeth foremost, said views being in side elevation and in vertical section upon the line 8—8 of Fig. 7 respectively;

Fig. 9 is a plan view broken away of a detail;

Fig. 10 is a sectional view on the line 10—10 of Fig. 7;

Figs. 11 and 12 are views in side elevation and vertical section respectively of the comb holder with a portion of the teeth omitted, the comb being inserted with its curved edge foremost;

Figs. 13 and 14 are views of the comb holder showing a modified support or stationary bar for the supplemental end combs;

Fig. 15 is an end view of the tube frame with the lock clamp attached;

Fig. 16 is a rear elevation of a clamp attached to the spool;

Fig. 17 is a plan view of the setting frame or spooling machine for the winding spools;

Fig. 18 is a front elevation thereof;

Fig. 19 is a sectional elevation thereof;

Fig. 20 is an enlarged view showing the relative position of the comb, reed and yarn;

Fig. 21 is a front elevation of a comb for holding the yarn;

Fig. 21^a is an end view of the same;

Fig. 22 is a side elevation of one of the sliding needles with the support therefor in section;

Fig. 23 is an elevation of a detail showing the swivel knife;

Fig. 24 is a plan with parts in section showing the support for the swivel knife;

Fig. 25 is a view, partly in side elevation and partly in vertical section, of the bracket for supporting the spool at the middle thereof;

Fig. 26 is an end sectional view of the spool holder of the tubing machine at the left side;

Fig. 26^a is an end elevation of the spool holder bracket at the left side;

Fig. 27 is a side elevation of the short spool holder showing the position thereof when a longer spool is employed;

Fig. 28 is a similar view with a short spool in place;

Fig. 29 is an end sectional view of the spool holder at the right side;

Fig. 30 is a perspective view of the tube clamp for holding the tube frame in position;

Fig. 31 is an end sectional view of the spool in the tube frame and the comb holder raised by its spring into normal position;

Fig. 32 is a plan view showing the adjustable bar or tube frame support;

Fig. 33 is a perspective view showing the right hand supplemental comb holding threads for the needles;

Fig. 34 is a vertical sectional view showing means for operating the front needle guides;

Fig. 35 is a side elevation of the spool releasing mechanism;

Fig. 36 is an end view of a sliding needle guide with the corner cut away so as not 5 to interfere with the yarn;

Fig. 37 is a vertical section showing the position of the needle after drawing the 10 yarn into the tubes and the position for placing the spool in the tube frame;

Fig. 38 is a vertical section showing the 15 position of the needle when starting back with the thread;

Fig. 39 is a vertical section showing the 20 position of the needle about to enter the tube;

Fig. 40 is a detail, partly in section and 25 partly in side elevation, of another feature of our invention; and

Fig. 41 is an end elevation of still another 30 feature of our invention.

In performing wide work an extra long 35 tube frame is customarily employed in conjunction with two, three or more spools of suitable length, the latter being serially 40 arranged in a suitable holder attached to the tube frame so that after the yarns are threaded through the tubes the spools remain in the holder in the same relation as heretofore and serve in effect as a single 45 spool from which the yarns are fed simultaneously through the tubes when in the loom.

In threading the yarns in the case of a 50 tube frame used for extra wide work and particularly where such tube frame is to be supplied with yarns from a series of 55 single spools, it is desirable to perform the tubing operation in a succession of operations, usually one threading operation for 60 each spool. That is to say, in the case of a tube frame requiring three spools of ordinary length arranged in a series, the threading of the yarns is best performed by first threading all the yarns of one spool 65 simultaneously through the tubes, then the yarns of the next spool, and finally the yarns of the third spool, the spools being then locked together upon the tube frame so that they may turn as a unit.

In the form of the invention herein described, there is provided a tubing machine 70 having devices for supporting a tube frame of the maximum length used for wide work so arranged that successive sections of the tube frame which are to be associated with successive spools may be successively placed in operative relation to a series or bank of needles, the needle bank being of lesser width than the length of the entire tube 75 frame, but the needles being sufficient in number to draw at one threading all the yarns on any one spool of the series which is employed. When any given section of the tube frame is placed in operative relation to the 80 needles, a spool, the yarn of which is to be 85

used to fill that particular section of the tube frame, may be placed in the spool holder of the machine and the needles projected through the tubes to seize the yarns and draw them through the tubes of that particular section of the frame. The spool may then be removed from the holder of the machine and placed in its holder in the tube frame, the latter shifted with relation to the needles and the operation repeated with the next spool, and so on until all the yarns of the several spools of the series have been threaded.

Referring to the drawings and particularly Figs. 2, 15, 16, 30, 31, 32 and 37 to 39, we have there shown a tube frame intended for wide work. This comprises the metallic tubes 1 supported on the frame 2, the latter being provided at each end with spring clips 2^a (Fig. 2) for holding the outer pintles of the end spools. Each such frame accommodates one or more spools depending on the width of the rug and the fancy of the manufacturer. In the present instance the tube frame 2 is shown as of a length requiring three or more spools 3, these being supported after the tubing operation, as usual in the clips 2^a and in the intermediate brackets, the latter shown in detail in Figs. 15 and 16.

As shown in said Figs. 15 and 16 each of 90 said intermediate brackets comprises a split journalled support 6 in which the pintles of adjoining spools rest. The upper portion 7 of said journalled support is pivoted or hinged at 8 so that it can be lifted and the spool inserted or withdrawn. A separate clip 9 herein constitutes means for fastening said hinged portion 7 to the fixed part 6 when a spool or spools are in place. At 95 each end of the tube frame 2 a tension spring 4 is provided secured to the front face of said frame and bearing against the spool head, thus tending to keep the spool from turning (Fig. 2).

Preferably the end faces of the spool 100 pintles have a clutch-shaped form whereby adjacent pintles may be fitted together thus locking the spools so that they will turn as a unit but permitting the spools to be separately inserted in or withdrawn from the tube frame as described in Patent #1,213,216 to Charles Lea, dated January 23, 1917.

In some instances the spools are not 110 formed with the clutch portion on the ends of the pintles, said ends being left plain thus allowing each spool to turn independently of adjacent spools. In this case the yarn is drawn through the tubes and the ends of the yarns sheared off for example, as is explained in Patent #1,153,865 to Hathaway and Lea, dated September 14, 1915, the successive spools being removed from the spool holders of the tubing machine (herein members 95 and 96) and placed in 115 the spool supports upon the frame after such 120 125 130

shearing operation. When all the spools of yarn have been threaded, sheared, and placed in the tube frame, the yarn ends all project through the tubes of the frames a 5 uniform length.

With interlocked spools, however, it is necessary to perform the shearing operation after the spool has been removed from the spool holders in the tubing machine and 10 placed in the supports therefor in the tube frame in order to make the ends of yarn of all the spools of uniform length. This is due to the fact that with such interlocking spools it may be necessary to give a spool 15 a portion of a turn after removing it from the spool holders of the machine in order to engage it with a spool previously positioned in the tube frame. Such turning would disturb the alignment of yarn ends.

20 In the present instance, to avoid said difficulty when employing interlocked spools, we preferably perform the threading and shearing of the yarns of each spool in two steps or operations of the machine for each 25 spool. Therefore, instead of allowing the needles to be entirely retracted and the yarn ends sheared as a continuous operation, the machine is automatically stopped after the 30 yarn has been drawn into the tubes but is still engaged with the needles. Said stopping is effected by an additional stop pin 49' which moves arm 50 (Figs. 2 and 5) to throw out the clutch as later explained in detail. The operator then removes the 35 threaded unsheared spool from the spool holders of the machine and places it in its support upon the tube frame. A lock or clamp described in detail hereinafter is then attached to the spool head and prevents the 40 spool from turning. With the threaded spool thus positioned in the tube frame the machine is again started and shears the ends of yarn, after the needles have entirely retracted and withdrawn from the yarn. The 45 machine then again stops automatically as in said Patent #1,153,865, ready for threading the next spool.

When spools with plain pintles and not interlocked are employed the machine obviously will operate faster if it is not stopped prior to the shearing operation. In such case, therefore, there is no additional automatic stop pin 49' for dividing the operation into two steps and also there is no need 55 of a lock or clamp attached to the spools.

Preparatory to the tubing operation the yarns are wound upon each spool by means of a set frame or spooling machine. We will now describe the preparation of the 60 tuft yarns in such spooling machine and prior to installation of the spools in the tubing machine. In this connection means is provided whereby the yarns after being wound upon a spool in the spooling machine 65 are held separated, in which condition they

may be placed in the tubing machine so that they may be readily and accurately drawn through the tubes of the tube frame.

Referring to Figs. 17 to 20 inclusive such separating device herein comprises a transfer or aligning comb 10 preferably formed of sheet metal and having along one edge a series of upright barbed teeth 11. The other edge of said comb opposite to that having the teeth is formed with a turned over portion 11a (Figs. 21 and 21a). Said transfer comb is so placed in the spooling machine with relation to the tuft yarns that, after the latter have been wound upon the spool, said comb may be applied to the yarns, indicated at 12, which are placed between the teeth 11 as indicated by dotted lines at 12a in Fig. 20.

For the purpose of illustration a common type of spooling machine 13 is indicated in 85 said Figs. 17 to 20, said machine being provided with mechanism for receiving a spool 14 and an idle roll 14a, and for winding tuft yarns about said spool in a well-known manner. During such operation the yarns unwind from bobbins, (not shown), and a reed or separator is provided having upright offset pegs 16 or the like for supporting the individual yarns or strands as they pass to 90 the spools.

As best seen in Fig. 20 it will be noted that said pegs 16 of the reed are offset near the bottom thereof, in such manner that the yarns 12a in following down between the pegs are pushed sideways into the comb 10 past the barbs of the teeth 11 thereof. The pegs to the left of the center of the reed are offset to the left, and those to the right of the center are offset to the right as clearly appears in Fig. 18. As herein shown the, 100 spool is narrower than the comb, the teeth of which must correspond exactly in distance from tooth to tooth with the distance between the tubes 1 of the tube frame 2 in order that the yarn may be positioned exactly for the threading operation. By offsetting the pegs 16 as shown, the yarns pass through the top or narrow part of the reed and on to the spool uniformly spaced and without danger of running off the edge of 110 the spool.

The transfer comb 10 is supported for the spooling operation with its teeth upright by means of a suitable comb holder 17 of the spooling machine, positioned immediately 120 below the tuft yarns at the point where the latter leave the reed in such manner that when said comb and reed are elevated together the strands of yarn are guided by the pegs 16 and pass exactly between the teeth 125 of said comb. Said comb holder 17 of the spooling machine consists of a cross bar provided with two or more studs 18 having a sliding fit in vertical slots 19 in the frame member 20 of the spooling machine. Such 130

construction permits a vertical movement of said comb holder 17 together with the reed so that the comb may be moved upwardly into contact with the yarn.

5 For raising said comb holder 17 and reed cam levers 21 are provided each pivoted at 22 upon the frame of the spooling machine and connected together by a link 23 to which is attached a transverse rod 24, one 10 on each side of the machine, at least one of said rods 24 having a handle 25. The lower surface of said comb holder 17 of the spooling machine rests upon said cam levers in such manner that when the levers are rocked 15 through movement of an operating rod 24 the comb holder 17 and reed are together lifted into the position indicated in part by dotted lines (Fig. 19). The holder 17 and reed are held in said lifted position by stop 20 pins 26 upon the machine frame against which the cam levers rest just after passing beyond their vertical position. Shifting of the operating rods 24 by the handle 25 in the opposite direction restores the cam levers to 25 their original or full line position allowing the reed and comb holder 17 to drop by their own weight or they may be pushed down if necessary by the operator.

After the comb 10 has been threaded it is 30 then withdrawn from the comb holder 17 of the spooling machine and is temporarily attached to the spool in any suitable manner as shown, for example, in the patent to Lea, 1,213,216 above mentioned. In this 35 condition the spools may be stored in quantity and used at the tubing machine as required. The comb shown herein is of the barbed tooth type which retains the yarn between the teeth thereof without the necessity of a cap or other yarn retainer.

Referring now to the tubing or threading machine proper and more particularly to the means for supporting the tube frame 2 therein the latter is carried by a tube frame 45 support 27 preferably of a width sufficient to afford support to said tube frame in the several successive positions of the latter while in the tubing machine. To this end said support 27 is carried upon the upright 50 frame members 30 and projects at either side for a considerable distance beyond the machine frame (see Figs. 1 to 4 inclusive). Said support 27 is braced by compression members 31, one at each end of the support 55 (see Figs. 3 and 4). Projecting fingers 32 are provided to assist in supporting said tube frame support and to prevent it from tipping backwards (see Figs. 1, 2 and 5).

Upon the upper surface of said tube 60 frame support 27 is fastened an adjustable bar or plate 33 (see Figs. 31 and 32). Said plate 33 is formed with transverse slots 34 which receive screws upon the support 27 thus enabling said plate to be shifted in and

out relatively to the support 27 to vary the 65 lengths of the ends of yarn in accordance with the requirements of the operator. Any other suitable mechanism may be employed for this purpose.

Properly to align the tubes 1 in that section of the tube frame which opposes the threading needles suitable stops are provided. At the left end of said support (see Fig. 1) there is fixed a stop 35 adapted to receive the left end of the tube frame in which position the right end of said tube frame is placed approximately in the correct position for threading the right hand end or first spool, looking in the direction of Figs. 1 to 4.

The tube frame 2 is forcibly clamped in position for threading by any suitable means. Herein for the purpose an arch 36 is supported above the tubing machine by means of said uprights 30 and upon said arch are bolted bearings 37 (Figs. 3, 4, 5 and 6), having adjustable eccentric bushings 38 for vertically adjusting the position of a shaft 39 supported therein. Upon said shaft 39 are pinned eccentrics 40 (Fig. 6), operatively connected with vertical arms 41 fastened at their lower ends by pins 42 (see Fig. 37) to bearings 43 provided on a horizontally extending bar 44.

Said bar 44 is grooved or notched upon its lower surface, being provided with teeth cut to the same pitch or spacing as the tubes 1 of the tube frame, as clearly shown in perspective in Fig. 30. Projecting hand levers 45 are provided upon shaft 39 for rocking the same thereby to force said bar 44 downwardly causing the downwardly projecting teeth thereon to enter and fit the space between the tubes, thus aligning the tube frame in an operative relation to the needles and forcibly clamping it in position.

It will be noted that said arms 41 for supporting the bar 44 are positioned at about one-fourth of the distance in from each end of said bar in order to distribute the pressure more evenly upon the tubes instead of applying said pressure merely on the ends of the bar 44. Said bar 44 thus holds the tubes and tube frame in position for the needles to enter during the threading process.

In order delicately to adjust said grooved or notched bar 44 endwise to place it in the exact desired position we herein provide a block 46 at each end of said bar. Each of said blocks is formed with a longitudinal slot 47, (Figs. 1, 2 and 30) through which passes a screw for bolting the block to the bar in the desired position of adjustment. The side or end face of each of said blocks rest against bearings 48 upon the frame of the tubing machine, one at each side of the machine thus preventing

said bar 44 from shifting endwise and keeping it in perfect alignment for the needles to enter the tubes.

In performing the tubing operation the 5 tube frame 2 is placed in the machine upon the support 27 with that section of the tubes through which it is desired to pass the yarns from the first spool in alignment with the needles. The drawing-in may be started 10 at either end of the tube frame but herein we have represented the operation as being carried out by first threading the tubes at the right hand end section of the tube frame as viewed in Figs. 1 to 4. The left 15 end of the tube frame is accordingly positioned against stop 35 (Fig. 1), the left hand and intermediate sections of the tube frame (not fully shown in Figs. 1 to 4 for the sake of clearness) overhanging and projecting along the support 27 beyond the 20 left hand side of the machine.

With this position of the tube frame a spool is placed in the spool holders of the tubing machine (herein members 95 and 96, 25 more fully described later) and the threading operation is performed substantially as described in said Patent #1,153,865 with the exception that the machine is stopped in the position indicated in Fig. 37 after the 30 needles have come forward and engaged the yarn as shown in Fig. 38 and have then retracted to a position with their ends just out of or to the rear of the tubes. Said stopping is effected by means of a pin 49 (Fig. 2) engaging and lifting a lever 50 and unclutching the main drive shaft in a manner described later more fully. With the needles in this partially retracted position (Fig. 37) the spool is taken out from 40 said spool holders of the tubing machine and is placed in the spool supports upon the tube frame 2 and a clamp 50' (Figs. 15 and 16) is attached to the spool head to prevent the spool from turning.

45 Such a clamp 50' is shown in attached position in Figures 15 and 16 in which position it holds the spools 3 from rotating when the tubing machine is again started and the needles further withdrawn beyond the 50 position indicated in Fig. 37 and the shearing of the ends of the yarn effected, which operations will later be explained more fully. Said clamp 50' is provided with a tongue 51 which fits under the spool support or 55 bracket 6 upon the tube frame 2 and also has a yoke portion carrying two screws 52 provided with ferrules 52' at their lower extremity which fit the spool heads, one of said ferrules seating upon the first positioned spool and the other upon the head of the next adjacent and subsequently positioned spool.

60 After said clamp 50' has been attached, the tubing machine is again started and the 65 yarn is withdrawn from the needles by the

further retreat of said needles beyond the position shown in Fig. 37. The ends of the yarn are then sheared off by means of a movable knife 53 and cooperating stationary knife 54 (see Figs. 6 and 37) all of 70 which will appear more fully hereinafter.

The first or right hand spool having thus been threaded and left positioned in the tube frame said tube frame is then unclamped by moving the handle 45 to release 75 bar 44. The tube frame is then moved along the support 27 and herein toward the right, carrying with it said first spool whose yarns have been drawn in and sheared, until an adjacent or intermediate section of the tubes 80 upon said frame is brought into registration with the needles. Such registration is accomplished by means of a stop 55 (Fig. 2) pivotally supported upon the tube frame support 27 by means of pin 56 and held 85 in the path of the frame by spring 57 but prevented from protruding too far outside of said support by means of a stop 58 upon said support.

The tube frame is then clamped in said 90 new position by downward movement of the grooved bar 44 and the operation is repeated with reference to a second spool which in turn is first placed in the spool 95 holders of the tubing machine, the yarns drawn in and the spool then placed in the second pair of spool supports upon the tube frame moving from right to left thereof as viewed in the figures. During the threading of said second spool the section of the tube frame at the right end thereof which has already been threaded rests upon that portion of the support 27 which projects at the right end of the machine. In Fig. 2 a portion of the first threaded or right 100 end spool is shown.

After the threading of said second spool is completed, which also preferably takes place in two steps as described in connection with the first spool, the tube frame is again unclamped and shifted to the right, being relocated by another intermediate stop similar to stop 55 or if this is the last or left end spool by means of stop 59 (Fig. 2) so positioned that when the right end of the tube frame abuts said stop 59 the unthreaded left hand section of tubes is brought into proper alignment with the needles, in which position the threading operation is repeated. The individual tubing operations for the various spools and the mechanism for performing the same are substantially the same as described in 110 Patent #1,153,865 above mentioned.

115 Referring more particularly to the detail 125 of the needles and associated mechanism it will be understood that a needle 60 is provided for each tube of any one section of the tube frame which is simultaneously threaded, as clearly appears in Figs. 1 and 130

2. As best shown in Fig. 6, each needle 60 is fixedly secured at its rear end in a cross bar 61 itself secured at each end to a slide bar 62 adapted to slide through guide ways upon the machine frame. Each of said slide bars 62 is provided upon its lower surface with rack teeth 63 (Fig. 6) which mesh with gears 64 secured upon the operating shaft 65.

10 Said operating shaft 65 is provided with a pinion 66 on one end thereof (Figs. 1 and 3) which meshes with a segmental gear 67 carried by a lever arm 68 pivoted upon the tubing machine frame at 69 and having 15 at its rear end a cam roll 70 which engages a track cam 71. Said cam 71 is secured upon a counter shaft 72 and is provided upon its outer circular periphery with gear teeth 73 meshing with a pinion 74 upon the 20 main drive shaft 75. Power is applied to said shaft 75 through suitable clutch and pulley mechanism (Fig. 2) and through the above described gearing causes the needles to advance and retract, the cam 71 being 25 so shaped as to cause a complete reciprocatory movement of the entire bank of needles for each revolution of said cam.

The power may be applied to the main shaft 75 by the operator at will through 30 said clutch and pulley devices which are similar to those described in said Patent #1,153,865. As shown herein the main drive shaft 75 is provided at its outer right hand end with a hand wheel 200 for turning 35 the same by hand to provide for the manual operation of the machine. Said shaft 75 is also provided with a driving pulley 201 loosely mounted thereon and to which power may be applied from any suitable source 40 through a belt.

Any suitable form of clutch is provided to cooperate with said driving pulley 201 and herein there is fixed upon the driving shaft 75 in position to cooperate with said 45 pulley 201 a split internal expanding ring clutch member of the well-known type having a wedging member adapted to be moved into position to clutch the pulley 201 to said ring member by longitudinal movement of a tapered expanding member 202. The latter is slidably mounted upon the driving shaft 75 at the side of the pulley and is adapted to be moved lengthwise the shaft by the yoke 203 which is provided 50 with pins 204 engaging a circumferential groove 205 in said expanding member 202. When said yoke 203 is rocked by means of the horizontal rock shaft 206 which extends from front to rear of the machine and is 55 supported in suitable journals 207 upon the machine frame, it serves to slide the expanding member 202 thereby to grip the internal expanding ring to the driving pulley 201.

To rock said yoke 203 there is provided 60 an operating lever 208 fixed to said rock

shaft 206 and having a handle 209 at its outer extremity and located conveniently just below the position of the spool when installed in the holders of the machine. Having installed a spool and yarns in the 70 machine the operator can start the machine by merely dropping his hand and pressing down on the lever handle 209. Said handle also serves as an emergency cut out so that the operator can if required at any time 75 shut off power from the machine and stop the latter by lifting the hand lever to release the clutch.

Means is herein provided whereby if the hand lever is not moved the machine will 80 automatically throw out the clutch on completion of the retractile movement of the needles. To this end the rock shaft 206 at its rear end is provided with an arm 50 already mentioned which carries a small 85 frame piece 210, the latter serving as a holder for a catch 211 which when the clutch is thrown in lies within the path of a stop pin 49 projecting from the face of the adjacent cam 120 (see Fig. 2). Just before 90 the cam shaft 72 has turned fully to retract the needles said catch is engaged by said pin 49 and lifted. The catch, however, is carried by a block 212 having a sliding movement in a slot 213 formed in said 95 frame 210 so that the block moves upward, then contact with the end of the slot, lifts the arm 50 thereby giving a slight turning movement to the rock shaft 206.

Said turning movement is sufficient to 100 loosen the frictional hold of the expanding member 202 and thereupon the spring 214 secured at its upper end to an arm 215 projecting from the tube frame support 27 and at its lower end to a lever arm 216 105 fixed upon the rock shaft 206 will throw the clutch completely out of engagement as the needles reach their rearmost position. Said lever 216 is provided at its outer end with a spring pressed catch 217 which when 110 the clutch is thrown in is adapted to engage in a suitable notch 218 upon the machine frame to hold the clutch in said position. For the purpose of stopping the machine with the needles in the position shown in 115 Fig. 37, and in order to divide the threading operation into two steps as is desirable when interlocked spools are employed, the additional stop pin 49', already mentioned, is provided upon the cam 120, and cooperates 120 to move arm 50 in a manner similar to that of pin 49.

In order to stop the machine from overrunning due to the momentum thereof when 125 the clutch is thrown out the driving shaft 75 is also provided with a brake drum 218 which is encircled by a brake band 219 held stationary at one end and at its opposite end secured to a block 220 which latter is fixed to an arm 221 keyed or otherwise fixed 130

to the rock shaft 206. When said rock shaft is turned to throw in the clutch said brake band is released, and when turned to throw out the clutch the brake band is applied.

5 For maintaining the proper separation of and guiding the needles there is provided a sliding guide bar 76 best seen in Figs. 5 and 6. Said guide bar is supported at its opposite ends by slide rods 77 and during a portion 10 of the movement of the needles is caused to advance with the needles and at another time the needles are caused to move relatively to said guide bar. As the needles 60 advance said guide bar 76 and slide rods 15 77 advance with the needles due to the frictional engagement between the needles and the guide bar. Said frictional engagement we have increased by the provision of ball 20 detents 78 adapted to seat in notches in said slide rods 77 and pressed upon by springs 25 79 (see Fig. 5). The guide bar 76 thus advances with the needles until the hooks of the needles have entered the tubes and the guide bar substantially abuts the ends of 30 said tubes.

The guide bar 76 is prevented from hitting the rear ends of the tubes 2 by means of collars 80 fixed upon the rods 77 near the rear end thereof and which bring up 35 against the right hand face of stationary sleeves 80^a formed in brackets 80^b upon the machine frame. Thereupon the sliding guide bar 76 remains stationary and the needles 60 advance relatively thereto and through the tubes into the position indicated by dotted lines in Fig. 6.

On retraction, the needles and the guide bar 76 are moved rearwardly together due 40 to the frictional engagement of the needles with said guide bar, said simultaneous rearward movement continuing until an adjustable collar 81 upon each slide rod 77 strikes the left face of said stationary sleeves 80^a. Thereon rearward movement of the guide 45 bar 76 is halted while the needles retract still further and relatively to said guide bar into their former position as shown in full lines in Figs. 5 and 6. Said guide bar 76 preferably has at each end a cutaway portion as shown at *x* in Fig. 36 so as not to 50 disturb the yarns which may have been already drawn by previous threading operations when the bar is moved forward into close proximity to the tubes.

55 As broadly disclosed in said Patent 1,153-, 865, means is provided at the outer or forward ends of the tubes, between the tubes and the yarns, for guiding and aligning the needles as they emerge from the larger or outer ends of said tubes. Herein said means includes a notched or grooved guide bar 82. We have herein improved the construction and manner of operating said guide bar to insure guiding of the needles up to the time

they pass forwardly through the strands of 65 yarn during each threading operation.

As shown herein said bar 82 is supported for guiding movement in vertical guides 83 at each end of the bar, said guides being formed upon the projecting bearings 48 secured to the machine frame. Said bar 82 is normally held in raised position out of the path of the needles by means of springs 84 secured, as by screws, to said bar one at each end thereof. The outer ends of said 75 springs rest upon said guide bearings 48, as clearly appears in dotted lines in Figures 3 and 4.

Attached to each end of said guide bar 82 for vertical movement therewith is a bolt 80 85 (see Fig. 34) engaging at its upper end a cam lever 86 pivoted at 87 upon the arms 41 which support the grooved clamping bar 44. Said levers 86 are adapted to be moved by adjustable plates 88 attached to the bar 85 89 which carries the movable knife 53, said plates engaging said levers 86 when said knife bar 89 is in its uppermost position. Said bolts 85 are thus moved downwardly carrying with them the attached guide bar 90 82 thereby to guide the needles during the end portion of their forward or outward stroke and also for a period when the needles retract.

The construction of the vertically movable 95 guide bar 82 appears clearly in Figs. 13 and 14. A forwardly protruding lip 82^a extends the entire length of the bar and is provided with grooves 82^b which guide the needles and separate them, thus spacing them evenly 105 and so holding them until the needles have passed through between the separate strands of the yarn. Said lip 82^a extends forwardly under the holder 107 which holds the transfer comb 10 in the tubing machine, and is 110 sufficiently narrow vertically to permit said comb holder 107 to be positioned very closely above the needles.

As the needles 60 advance and are about 115 to emerge from the large ends of the tubes the plates 88 upon the knife bar 89 engage the cam levers 86 and depress the vertically movable guide bar 82 into the position indicated by dotted lines in Fig. 34. Said guide bar 82 engages with the needles as they emerge from the tubes and wedges any of the needles that may be out of alignment into the required position. As the needles retract and said knife bar 89 descends 120 springs 84 return said guide bar 82 to its 125 normal position above and out of the path of the needles.

Means is provided for delicately adjusting the guide bar 82 including blocks 91 having slots 92 which receive bolts for adjustably securing said blocks to the guide bar 82 (see Fig. 4) in a manner similar to that in which the adjustment blocks 47 are 130

secured to the clamping bar 44 previously described.

Referring again to the needles and supporting mechanism therefor it is noted that 5 we have provided means for allowing a few needles at each end of the bank of needles to yield backwardly against springs which normally hold them in position in alignment with the remaining needles of the bank. Sometimes a spool head of a spool which has been previously threaded will lie directly in the path of such end needles. By permitting said end needles to yield we prevent them from breaking but still effect 15 the threading of said end needles and the end tubes, preferably with the aid of supplemental end combs described in detail later.

In Fig. 22 we have shown the cross bar 20 61 which supports the needles, said bar at each end being provided with a rearwardly projecting rod 93^a supporting for sliding movement a block 94 to which said end needles are attached. Said block 94 and its 25 needles are normally held in forward position by means of a coil spring 93 (see also Figs. 1 and 2).

After each drawing in operation, herein comprising two steps, a fresh spool is placed 30 in the spool holders of the tubing machine (herein members 95 and 96) and the operation is repeated until the tube frame has been completely threaded and filled with 35 spools. Said spool holders of the tubing machine are substantially of the same construction as shown in the Patent #1,191,109 to Charles Lea, dated July 11, 1916. In the present instance, however, we have provided means for holding various lengths of 40 spools or spools having different diameter of head, or both, and will now describe the same.

Suitably positioned upon the tubing machine frame and at the front thereof is a 45 pair of opposed cup-shaped holders 95 and 96 each adapted to receive one end of a spool during the first portion or step of the threading operation. Said spool holders 95 and 96 of the tubing machine are carried by brackets 97 and 98 at the left and right sides respectively of the machine and attached to the end side of the tube frame support 27 (see particularly Figs. 3 to 6, 26, 26^a and 29).

Each of said holders 95 and 96 is provided 55 with gear teeth meshing with pinions 99 and 100 respectively, carried upon the opposite ends of the common shaft 101. A spool may thus be turned to wind up any slack yarn, said turning being effected by 60 means of a suitable hand wheel 102 upon the short cross shaft 103 having a bevel gear 104 meshing with a similar bevel gear 105 upon the right end of said shaft 101. One of said holders, herein the right hand holder 65 96, is supported for sliding movement trans-

versely of the machine, being normally pressed towards the inserted spool by means of coil spring 106 (Fig. 4) thus permitting the ready insertion or withdrawal of a spool.

When a spool is about to be inserted in 70 said holders 95 and 96 of the tubing machine the transfer or aligning comb 10 is detached from the spool and sufficient length of yarn is unwound from the spool to permit the insertion of said comb 10 into the grooved 75 comb holder 107, in the manner shown in Figs. 2, 6, 7, 11, 12, 31, 33 and 34. Said comb holder 107 is supported for sliding movement and for this purpose has a bearing at each end in one of the overhanging 80 bearings or arms 48 already described, said comb holder and its groove being of sufficient length to receive and support the comb throughout the entire length thereof. The details of said sliding comb holder 107 and the manner in which the comb 10 is supported thereby will later be more fully described.

Some spools and particularly long spools 85 may have a tendency to bend in the center thereof when they are held from turning during the threading operation. To avoid such bending we have shown in Figs. 3 and 25 an intermediate support or bracket 108 which is attached to the under side of the 90 tube frame support 27.

For the purpose of holding in the tubing machine shorter spools than those normally employed we have provided an auxiliary 95 spool holder, best seen in Figs. 3, 27 and 28. Said auxiliary spool holder comprises a bracket 109 for holding the left end of such a short spool. Said bracket 109, which is secured upon and depends from the tube 100 frame support 27, carries a latch 111 pivoted thereto at 112 and provided with a transverse slot 110. Said latch 111 is normally held up against a shoulder 113 upon the bracket 109 by means of a spring 144. The left end 105 pintle of a short spool is inserted in said slot 110, the bottom of the spool resting upon the bracket 109 as shown in Fig. 28. When an ordinary spool of longer length is positioned in the machine such spool passes across said bracket 109, its left end being supported in the usual spool holder 95. With such a spool the latch 111 is depressed 110 into the position shown in Fig. 27 and lies below the spool as clearly appears in said 115 figure.

As stated, spools of normal length lie with their left end in the spool holder 95 which, however, is adjustable sideways or transversely of the tubing machine so that spools 120 of varying length may be accommodated by said spool holders 95 and 96. For this purpose the bracket 97 at the left end of the machine and which supports the spool holder 95 may be adjusted transversely of the machine, being movable in gibs 115 (see Fig. 125 130

26^a). A clamping screw 116 is provided for holding said bracket 97 in the desired position of adjustment.

The holders 95 and 96 are also adapted 5 to receive different diameters of spool heads and for this purpose each of said spool holders 95, 96 is provided with cup portions of different diameter, as clearly shown at 96^a and 96^b in Fig. 29. In said figure the right 10 hand spool holder 96 of the tubing machine is shown with a spool in position, said spool having a head of the diameter indicated by full lines at 118, while we have indicated by dotted lines at 119 the position which would 15 be occupied by a spool having a smaller head, and at 117 the position of a shorter and small headed spool.

As stated above the transfer or aligning 20 comb 10 is supported in the tubing machine in the groove of the comb holder bar 107 which latter is supported for sliding movement transversely of the tubing machine in the bearings 48. It is desirable that the yarns 25 lead from the comb in the comb holder 107 as herein shown at right angles or nearly perpendicular to the comb, in order that the needles 60 when moving outward beyond the front needle guide 82 shall pass through the 30 yarn strands correctly.

After the needles have passed forwardly or outwardly through said yarn strands the 35 comb holder bar 107 is given a lateral movement to cause each yarn to be laid in the bight of the adjacent needle. Said lateral movement is obtained by any suitable mechanism and as shown herein (see particularly 40 Fig. 2) a cam 120 is fixed upon the counter shaft 72 near the right end thereof, the groove of said cam cooperating with a roller 45 123 carried by a stud 122 at the upper extremity of a lever arm 121. Said lever arm 121 is fixed upon a short vertical shaft 125 supported in a bracket 126 upon the machine frame (see also Fig. 5). Secured to said 50 shaft 125 is a forwardly projecting horizontal arm 124 carrying an adjustable bar 127 provided with a slot in its forward or outer end in which seats a vertical pin 128 upon the right end of the comb holder 107 (see Fig. 2).

As the shaft 72 rotates the lever arm 121 is rocked by means of the cam path cut in cam 120 and cooperating roller 123, and in turn rocks shaft 125 and through members 55 127 and 128 shifts said comb holder 107 transversely of the tubing machine at the proper time. Said bar 127 carried by the arm 124 is made adjustable relatively to said arm because the comb holder 107 varies 60 somewhat in position with different styles of tube frames. As above pointed out the bar 33 (Figs. 31 and 32) upon the tube frame support 27 is also adjustable for a similar reason while the projecting bearings 48 at 65 each side of the tubing machine are of special

design or are adjustable relative to the machine frame through a bolt and slot connection in accordance with the position of the tube frame.

When the needles 60 are being retracted, 70 which movement takes place in a manner similar to that explained in Patent #1,191,109, it is desirable to provide a certain amount of slack in the threads or yarns to permit them to be drawn through the 75 tubes. This is effected by releasing the spool so that it may turn in the spool holders 95, 96 of the tubing machine and may unwind under the draft of the needles to provide the required slack. As shown most clearly in 80 Fig. 35 the spool while in the spool holders of the tubing machine is normally locked against unwinding movement by means of a pawl 130 which engages a ratchet 131 herein attached to the left hand cup-shaped spool 85 holder 95.

Mechanism is provided, however, whereby 90 said pawl 130 is lifted at the proper time to permit the spool to unwind. Herein for the purpose we have provided an adjustable two-part cam 132 fixed upon the counter shaft 72 (see particularly Fig. 6). Said cam 132 comprises two parts or discs placed 95 face to face and adjustable circumferentially relatively to each other to vary the effective extent of the raised portion 132' of the cam, thus to vary the length of time during which the pawl 130 is lifted, such variations corresponding to different lengths of tubes 1 100 in the tube frame.

Cooperating with the cam 132 is a cam roll 134 upon the inner end of a horizontally extending arm 133 loosely supported upon the shaft 75. The forward or outer end of said arm 133 has operative engagement 105 through an adjustable bolt 133' with a downwardly extending arm 130' rigid with said pivoted pawl 130. By turning one part of the cam 132 relatively to the other an adjustment is obtained of the interval of time 110 during which the effective raised portion 132' of said cam holds the cam roll 134 and inner end of the arm 133 down and consequently the outer end of said arm 133 and the pawl 130 up.

The cam 132 moves the lever arm 133 at the proper time to lift the pivoted pawl 130 and maintain the same in lifted position for a sufficient time to provide the necessary slack of the yarn. Said cam 132 is so positioned on countershaft 72 that the relaxation of the yarns will occur at the desired time and preferably at the time when the needles 60 retract to a position just within the tubes. The pawl 130 is then lifted, releasing the spool, and the yarns are unwound from the spool by the pull of the needles until said pawl is again dropped into the ratchet 131 when the raised portion 132' of the cam has passed off from the cam roll 132 120 125 130

134. The forward or left end of arm 133 is drawn downwardly by a spring 137 thereby permitting the pawl 130 to drop into and hold the ratchet 131. The spool is thus held 5 fixed through said pawl and ratchet mechanism preferably about at the time when the needles emerge rearwardly from the tubes. Said movements, however, may be varied to suit different working conditions.

- 10 With some spools it is desirable that they be placed in the spool holders of the tubing machine with the yarns drawn under. The position which would be occupied by yarns so placed is indicated by dotted lines in Fig. 15 6. In this instance the pawl and ratchet must hold in the opposite direction, to prevent the spool from turning in a counterclockwise direction, as viewed in Fig. 6. In order to reverse the pawl 130 there is preferably provided a bevel-toothed adjustable 20 steel piece 135 for engaging the ratchet with its straight face.

In the position shown in Fig. 35 said tooth or piece 135 prevents the ratchet and spool 25 from turning in a counterclockwise direction, viewing Fig. 35, and in a clockwise direction as viewed in Fig. 6. The ratchet and spool is free to turn, however, in the opposite direction if it is desired to turn the spool 30 through the hand wheel 102 (Fig. 5). Said bevel-toothed steel piece 135 is held near the end of pawl 130 by means of a set screw 136 which may be loosened to permit said piece 135 to be reversed or turned through 180° 35 so that its straight face will engage the opposite side of the teeth of the ratchet, thus reversing the holding effect of pawl 130 and preventing the ratchet and spool from turning in the opposite or counterclockwise 40 direction, viewing Fig. 6, as is desired when the spools are positioned in the tubing machine with the yarns drawn under.

Prior to use in the loom it is necessary to 45 cut the drawn-in yarns evenly at a fixed predetermined distance from the ends of the tubes. Herein shearing means is provided whereby this is accomplished automatically and during the second step of the threading operation, as previously mentioned, that is, 50 after the spool has been removed from the spool holders 95, 96 of the tubing machine and placed in its supports upon the tube frame 2. Said shearing means includes a vertically movable knife 53 carried by a 55 knife support bar 89 to which it is fastened by screws or otherwise and a cooperating stationary knife 54 secured upon the inner side face of the tube frame support 27 (see Figs. 6, 23, 24, and 37).

- 60 The yarn strands when drawn back by the needles lie directly over the upper edge of said stationary knife 54 and in that position are cut off by the downward movement of said vertically movable knife 53. 65 Said movable knife 53 has an inclined edge,

as seen in Figs. 6 and 23 particularly, and is adapted to receive a twisting or shearing movement relatively to the stationary knife 54. Said movable knife 53 carries at its left hand end, as viewed in Fig. 1, a depending cam member 140, best seen in Fig. 23, said cam member 140 having a lower beveled edge. The knife blades are so arranged that the movable knife 53 when in normal or elevated position lies with its forward edge somewhat over the edge of the stationary knife 54.

When said movable knife 53 is depressed the said cam member 140 first engages the stationary blade 54 thereby to cause the movable blade 53 to be wedged over. The knife support bar 89 and the blade 53 carried thereby are for this purpose supported for pivotal movement upon horizontal pivots at each end of said bar 89. Thus as each succeeding portion of the blade edges cross a shearing action is effected through the pressing over or twisting of the upper and movable blade 53, thereby giving in effect the action of a pair of shears and imparting 90 a clean shearing cut to the yarn.

To permit said wedging or twisting movement of the upper and movable blade 53 the support bar 89 carrying said blade, as best shown in Figs. 23 and 24, is provided at each end with a horizontal pivot 141 journaled in blocks 144 fixedly secured as by bolts 144' upon vertically reciprocable plunger rods 145, one at each side of the machine (see also Fig. 6). Said support bar 89 is normally held with its right hand portion (as viewed in Figs. 23 and 24) down and resting against a suitable stop 145a upon the plunger rod 145. A spring 142 is provided for so holding the bar 105 89, said spring being attached at its upper end to a rearwardly projecting lug 89' upon said support bar 89 and at its lower end to a stud 145b fixed to the plunger rod 145.

To impart suitable and properly timed movement to the vertically movable blade 53 and the transverse support bar 89 carrying the same the plunger rods 145, one at each end of said bar, 89, are guided for 115 sliding movement in upper and lower brackets 146, 147 respectively, attached to the frame members 30 and arch 36. One side of each of said plunger rods 145, and herein in the front, is toothed to form a rack 148 each of which engages with a pinion 149 (see Figs. 3 and 4) said pinions being secured to the shaft 65 which carries the main driving gear 66 and the needle operating gear 64. Said gears are so timed 120 that as the needles are retracted rearwardly out of the path of the shearing mechanism the movable knife 53 descends from the position shown in Fig. 37 to that shown in Fig. 6 and trims the ends of the drawn-in yarns. 130

When the needles are again advanced said upper knife 53 is lifted up and out of their path. As best seen in Fig. 6, a deflecting plate 150 is secured upon the machine frame and beneath the shearing mechanism to guide the ends of the yarn sheared off so that they may fall through an opening 151 cut in the base 151^a of the tubing machine and the table 151^b and into a 10 drawer, basket, or other suitable receptacle, not shown.

In practice it is not only necessary that the projecting ends of the drawn-in yarns shall be trimmed, but such trimming must 15 be exceedingly exact and even and at the required distance from the ends of the tubes. This is essential in order that the tube frame when withdrawn from the tubing machine or when shifted to thread the next succeeding 20 spool may have the yarns cut the required length and held fixed in this relation on the spool, thus being ready for the loom without the need of any further step or operation. To insure even shearing, means 25 is preferably provided so that before shearing and preferably during the shearing operation the ends of the yarn strands are held clamped and also the tube frame itself held securely in position.

30 For so clamping the yarn strands during the shearing operation clamping or holding means is provided between the small or inner ends of the tubes 1 and the shearing mechanism. Such clamping means may be embodied in various forms but herein we have 35 provided a clamping or holding bar 152 extending transversely across the tubing machine and carried by the shearing mechanism in such manner that when the needles 40 are advanced said clamping or holding bar 152 is elevated with the movable knife 53 and out of the way. As the needles are retracted, however, and the movable shearing blade 53 descends said clamping bar 152 45 is brought down across the drawn-in yarn ends, thus clamping them tightly against the flat top surface of the support 27 and the adjacent flat upper surface of the stationary knife 54. This is also the position 50 for starting the tubing machine.

Referring more particularly to the detailed construction of said clamping or holding bar 152, as best seen in Fig. 6, said bar is fixedly secured to the slotted lower ends of 55 two or more vertical plunger pins 153 distributed transversely of the tubing machine and along the knife support bar 89. Each of said plunger pins 153 is provided with a coil spring 154 compressed against the overhanging arms 155 fixed upon said knife 60 supporting bar 89 and acting to depress the clamping or holding bar 152 to its lowermost or clamping position. Each of said pins 153 carries a collar 156 which has abutting contact with the upper face of its sup-

port arm 155 thereby to limit downward movement of the holding bar 152.

On depression of the shearing blade 53 and its supporting bar 89 said holding bar 152 clamps the drawn-in yarns just prior 70 to the shearing cut subsequent depression of the blade 53 resulting merely in compressing to a greater or less degree the coil springs 154. Said holding or clamping bar 152 may be of any suitable material and shape but 75 preferably and herein it is formed of a metal strip or plate having a lower rounded edge.

In order that the yarns may be released 80 from the holding bar 152 to permit the withdrawal of the tube frame carrying the threaded spools from the tubing machine, or to permit shifting of the tube frame, while still having the needles retracted and the shearing blades depressed, means is provided whereby said clamping or holding bar 152 may be independently lifted to release 85 the yarns without moving the main operating mechanism or lifting the shearing blade 53. 90

Herein such release is effected simultaneously with the releasing movement of the tube clamp 44 (see particularly Figs. 6 and 37). For this purpose each of said collars 156 upon the plunger pins 153 is provided with a forwardly extending finger 157 which overlies the tube clamp 44 as shown in Fig. 6 so that when the latter is moved upwardly by the handles 45 the upper side of said tube clamp 44 will engage an adjustable screw 158 carried by said finger 157 thereby to lift the holding bar 152 against the compression of the springs 154. The yarn ends are thus free to be withdrawn from the 100 machine with the spool and the tube frame. 105

In operation and as has been already pointed out, the tubing machine is stopped when the needles have retreated to the position shown in Fig. 37. The operator at that time removes the spool from its holders 95, 96 in the tubing machine, winds up the slack 110 yarn thereon and then applies the spool to the supports in the tube frame. If the spool occupies an intermediate position on the tube frame one of its pintles, herein that 115 at the right end of the spool, is engaged with the clutch-like portion on the face of the adjacent spool previously threaded and placed in the tube frame. The spool then occupies the position shown in Fig. 31. A 120

clamp 50' (Figs. 15 and 16) is attached to prevent the spool from turning and the operator then again starts the machine to perform the second step of the threading operation. The needles begin to retract and 125 tighten the yarn, the spool being prevented from turning by said clamp 50' and the yarns are withdrawn from the eyes of the needles as said needles retract further. Then 130 the yarn clamping or holding bar 152 above

described descends to hold the ends of the yarn during the shearing operation.

We will now describe in detail the mechanism for holding the transfer or aligning comb 10 in the sliding comb holder or holding bar 107. In some instances it is desirable in order to facilitate winding of the spools in the said frame or spooling machine that the spools be wound under. The position that would be occupied by the yarn in such case is indicated by dotted lines in Fig. 19. This is done in order that the spool will have the different colored strands of yarn so placed on the spool that turning of the spool over end for end will reverse the design in accordance with the dictates of the rug pattern, as compared with a spool having the yarn wound over as shown in full lines in said Figure 19. With an under-wound spool which has been reversed the yarn will still lead from the spool when attached to the tube frame into the tubes as shown in Figs. 15 and 31.

In reversing or turning the spool over the comb 10 is also turned over or reversed with the spool so that the turned-over edge 11^a of the comb extends downwardly. It is therefore necessary that means be provided for holding said comb 10 in the comb holder 107 of the tubing machine with the teeth 11 of said comb foremost and the turned-over edge 11^a beyond or outside said comb holder 107 (see Fig. 8) and also alternatively for holding the comb in inverted position with its turned over edge 11^a inserted into the comb holder 107 as indicated in Fig. 12.

In Figs. 7 and 8 the comb 10 is shown inserted and held in the comb holder 107 with its teeth foremost. Means is provided whereby the comb will be inserted only to such a depth as to leave enough of the bottom of the teeth outside the comb holder 107 to let the yarn strands withdraw easily from the comb and not cause them to bind against the comb holder. To accomplish this purpose and also to hold the comb in the inserted position shown in Fig. 8 there is provided upon the front face of the central or main part of the comb holder 107 a sliding bar 162 having inclined slots 162' which receive horizontally projecting studs 163 upon the comb holder 107. Said bar 162 because of its inclined slot and pin connection with the comb holder 107 may be slid relatively to the comb holder the inclination of the slots 162' also causing a vertical movement of the bar 162 relatively to the comb holder 107. Said bar 162 constitutes a means for holding or clamping the comb 10 when said comb is inserted with its teeth foremost.

For preventing the comb from being inserted too far there are provided upon the rear face of the sliding bar 162 a plurality of spaced vertically slidable rectangular-

shaped blocks 164. Said blocks 164 are received in vertical slots cut in the rear face of the sliding clamping bar 162 and each block 164 is provided at its upper end with a pin 165 which engages one of a plurality of cams 166 having a horizontal portion at each end thereof and an intermediate inclined portion, said cams 166 being supported upon the top of the comb holder 107. A handle 167 is provided for moving the clamping bar 162.

When the clamping bar 162 is moved to the left by means of said handle 167 the blocks 164 also move to the left and ride down the inclined portion of the cams 166 into the position shown in Figs. 7 and 8, thus forming stops to prevent the comb 10 from entering too far and so positioning it as to leave the bottom of the teeth outside of the comb holder 107. Movement of the clamping bar 162 to the left also causes downward movement thereof, sufficient space being left to insert the comb 10.

When the comb 10 is inserted with the turned-over edge 11^a foremost as shown in Figs. 11 and 12 the clamping bar 162 and the vertically slidable stops 164 are left in raised position and toward the right of the comb holder, as shown in Fig. 11. From a comparison of Figs. 8 and 12 it will be noted that when the comb is inserted with the turned-over edge foremost it is moved in to the bottom of the groove in the comb holder 107, the greater portion of the comb and its weight being then within the comb holder. Less positive clamping or holding means is therefore necessary in this instance. For holding the comb in the position shown in Figs. 11 and 12 we have provided a plurality, herein two, spring-pressed ball detents 107^a which are adapted to rest upon the upper surface of the comb and hold it when inserted with its turned-over edge foremost.

With the comb here shown the distance from one end thereof to the first yarn is not the same as that from the other end of the comb to the first yarn, as apparent in Fig. 21, wherein the distance *a* is not the same as the distance *a'*. In order that the comb will be positioned in the comb holder with its teeth in proper alignment for the drawing-in operations and to permit the needles to pass through between the yarn strands in whichever way the comb is inserted we provide fixed blocks or stops 160 and 161 and a movable stop in the form of a hook shaped piece 161^a. Said fixed stops 160 and 161 at opposite sides of the machine are so located as to receive between them and properly position the comb 10 when it is inserted with its turned-over edge foremost, as in Figs. 11 and 12. When the comb is inserted in the reverse manner, with teeth foremost as in Figs. 7 and 8 its left end is placed against fixed stop 160 which is provided

with a cut out portion in which the comb rests, while its right end is held by said movable stop 161^a. Said movable stop 161^a is secured upon the right end of the sliding 5 clamping bar 162. In the position of the comb shown in Figs. 11 and 12 said movable stop 161^a lies to the right of the comb and out of the way, but is moved to the left with the bar 162 when the comb is inserted as in 10 Figs. 7 and 8. Thus in Figs. 11 and 12 the two fixed stops 160 and 161 cooperate to position the comb 10, while in Figs. 7 and 8 the fixed stop 160 and movable stop 161^a cooperate for said purpose. In Fig. 10 we 15 have shown in cross section a latch 162^a which assists in holding the comb in position.

Sometimes the bearings at the ends of the 20 spools for supporting the same in the tube frame may interfere with the yarns making it necessary more positively to separate the end yarns to enable the needles to pass through between the same. To accomplish such separation we herein provide a supplemental 25 adjustable comb at each end of the bank of needles.

Said supplemental combs 167' in that construction shown in detail in Figs. 7 to 12 are carried by uprights 167^a attached to the 30 comb holder bar 107. Said supplemental combs 167' are movably attached to said uprights 167^a by pivots 168 so that they may be swung down into the position shown by dotted lines in Fig. 12 or may be swung up 35 out of the path of the spools, as shown by full lines in said figure, and also in Figs. 7, 8 and 11.

Each of said combs comprise a comb portion proper 167', adjustably supported in 40 the pivoted member 167''. Springs 169 secured to the uprights 167^a are provided, having sufficient tension to hold the combs in either position of adjustment. Said supplemental combs may be swung down and 45 pressed into the yarn slightly below the comb 10. The comb portion proper of each comb may then be moved relatively to the pivoted member 167'' which supports said comb portion by means of a slot 170 thus allowing said supplemental combs to be depressed still further in order to be out of 50 and below the path of the needles during their movement. A spring pressed ball detent 173 (see Fig. 12) is provided for holding the comb portion 167' in the desired 55 position of adjustment relatively to the pivoted members 167''. Said supplemental combs keep the end strands of yarn straight and separated so that the needles will pass 60 through properly without tangling the yarns and are caused to draw the yarns through the proper tubes.

When the supplemental combs 167' are 65 mounted directly upon the comb holder 107 as in the construction shown in Figs. 1 to

12 it is desirable that the right hand supplemental comb be somewhat differently supported from that at the left hand of the bank of needles so that when the slidable comb holder 107 is shifting to the right to 70 lay the strands in the bights of the needles said supplemental right end comb will not interfere with any spool lying to the right thereof which may have been previously threaded and attached to the tube frame. 75 Therefore said right end comb is so supported as to be able to move or yield to the left at the bottom portion thereof, as indicated in dotted lines in Fig. 4.

For this purpose, as best seen in Fig. 33, 80 the pivoted portion 167'' of said combs is provided near its end with a pair of relatively movable plates 170^a and 170^b secured together by pivot pin 171 and a screw 172 carried by the rear plate 170^a and movable 85 in an arcuate slot 172' formed in the plate 170^b. Said pin and slot connection limits the swinging movement of said comb upon the pivot pin 171 and prevents excessive play between the parts. 90

In Figs. 13 and 14 we have shown a preferred form of support for the supplemental combs 167'. In the construction shown in said Figures 13 and 14 there is provided a supplemental stationary bar 174 secured at 95 each end thereof to the machine frame. With this construction it is unnecessary to provide a yielding support for the right hand end comb as above described because the said combs in this instance do not interfere with the spools and thus duplicate combs may be used at either side of the machine. 100

In the drawing-in operation it sometimes occurs, particularly where the yarns are of 105 a fuzzy character or have protruding fibres, that the needles 60 when moving forward or to the left, as viewed in Fig. 6, will engage with their points such protruding fibres of the yarns and therefore tend to 110 cause slack in the yarns and to interfere with the proper drawing-in movement of said needles. In order to overcome this we have provided means whereby the yarns may be temporarily tautened at, or substantially at the time when the needles 60 move forwardly or to the left. 115

While for this purpose any suitable means may be provided we have herein shown (see particularly Fig. 40) a ratchet 175 fast upon 120 the shaft 101 mentioned above, said shaft also having fast thereon a pinion 176 meshing with teeth 95^a formed upon the spool holder 95. Loosely carried upon said shaft 101 preferably at one end thereof is a lever 125 arm 177 having pivoted upon it a pawl 178, the outer end of said pawl being connected with said lever arm 177 by a spring 179. Near the outer end of said lever arm 177 is a pin 180 received in a slot 181 formed in 130

a lever 182 pivoted at 183 upon the framing of the machine. A spring 184 tends to lift the longer arm of said lever 182, said lever also being provided with a heel or projection 185 at the upper or forward end thereof. The opposite end of said lever 182 is adapted to be engaged by a pin 186 upon the lower end of the rack 148. The construction and arrangement of parts are such that upon the upward movement of the rack 148 the pin 186 engages the adjacent arm of the lever 182, thereby rocking said lever and consequently the lever 177, thus causing the pawl 178 to rotate the pinion 176 in a direction to tighten the threads. Such tightening action is momentary only and for the purpose stated. At the extreme end of the throw of the lever 182 in the described connection, the projection or heel 185 strikes the pawl 178 and disengages the same from the ratchet 175, thus permitting the proper feeding or playing-off of the yarns or threads when the needles 60 engage the same and are moved toward the right viewing Fig. 6.

It is desirable, whenever a fresh spool is placed in the holder of the machine or whenever the spool is taken out and replaced, that the same have the same circumferential position that it previously occupied or a position removed therefrom ninety degrees. For that purpose, any suitable indicating or marking means may be employed. In Fig. 41, we have represented a disk 187 which is fast upon that casing in which the holder 95 or 96 is positioned. The star wheel 188 is fast upon the shaft of the spool and a projection 189 upon the disk 187 is adapted to register with any desired tooth of the star wheel for the purpose set forth. In this or in any other suitable way the proper circumferential position of the spool may be secured.

Having thus described one illustrative embodiment of my invention, I desire it to be understood that although specific terms are employed, they are used in a generic and descriptive sense and not for purposes of limitation, the scope of the invention being set forth in the following claims.

Claims—

1. In a machine for placing tuft yarns in carpet manufacture through the tubes of a tube frame for use in wide work, the combination of a tube frame having means for supporting a series of spools end to end, a support for a single spool upon the machine, said support adapted to receive each spool of the series successively, means for drawing in the yarns of each spool through a section of tubes of the frame while the spool is so supported, means for interengaging the ends of adjacent spools the yarns of which have been drawn in, said spools being positioned in said supporting means of the tube

frame, and means for holding the spools from turning while in said frame.

2. In a machine for placing tuft yarns in carpet manufacture through the tubes of a tube frame, the combination of a tube frame, a tube frame support upon the machine, a series of needles for drawing the yarns through the tubes of said frame when positioned upon said support, and an adjustable elongated member carried by said tube frame support and shiftable transversely with relation to said support whereby the desired distance between the tubes and the advanced needles may be provided as determined by the length of yarn to be drawn.

3. In a machine for placing tuft yarns in carpet manufacture through the tubes of a tube frame, a support for the same upon the machine, means for clamping the frame in position upon its support, said means including an overhead longitudinal member, a horizontal and vertically adjustable shaft supported for rocking movement in said member, eccentrics carried by said shaft, depending arms operatively related to said eccentrics for vertical movement thereby and a tube frame clamp and aligning bar carried at the lower extremities of said arms.

4. In a machine for placing tuft yarns in carpet manufacture through the tubes of a tube frame for wide work, the combination of a tube frame having tubes and adapted to receive a plurality of aligned spools of ordinary length, supporting means above the tube frame and extending longitudinally of the machine, bearings carried thereby, adjustable eccentric bushings carried by said bearings, a shaft supported by said bushings, eccentrics upon said shaft, depending arms loose upon said eccentrics, a toothed clamping bar connected to said arms, and means manually to turn said shaft to move said bar into tube frame clamping position, said arms being positioned longitudinally of the frame so as to distribute evenly the clamping pressure upon the tube frame.

5. In a machine for placing tuft yarns in carpet manufacture through the tubes of a tube frame, the combination of a tube frame, tufting tubes carried thereby, a notched clamping bar to engage the tubes, supporting means for said clamping bar, and means for manually adjusting said clamping frame bar in a longitudinal direction, whereby the notches thereof may be brought into accurate register with the tufting tubes, said means including members connected at each end of said bar and adjustable longitudinally with relation thereto, said members cooperating with the tubing machine frame accurately to position the clamping bar and the tube frame.

6. In a machine for placing tuft yarns in carpet manufacture through the tubes of a tube frame for use in wide work, the com-

- bination of a tube frame of a length to support a plurality of aligned spools of ordinary length, tufting tubes carried thereby, means to support said frame in different positions longitudinally of the machine to permit the drawing of yarns successively through different sections of tubes, means to clamp the tube frame in said different positions, said tube frame being adapted when unclamped to be moved upon its supporting means longitudinally of the machine, and a movable stop adapted to be positioned in the path of movement of the tube frame to cause an intermediate section 15 of tubes upon said frame to be aligned for drawing of the yarns through the same.
7. In a machine for placing tuft yarns in carpet manufacture through the tubes of a tube frame the combination of a series of tufting tubes, a cooperating series of needles, reciprocable means to support said needles, a sliding guide bar for the needles, slide rods for supporting said guide bar to permit it to advance with the needles, and holding means engaging said slide rods and said reciprocable needle support to insure the forward movement of the needles and said guide bar in unison but permitting subsequent relative movement between them.
8. In a machine for placing tuft yarns in carpet manufacture through the tubes of a tube frame the combination of a series of tufting tubes, a cooperating series of needles, a sliding guide bar for said needles, means for causing said member to advance with the needles during a portion of the forward movement of the latter but permitting subsequent relative movement between them, and means for holding said guide bar to the rear of but adjacent the tufting tubes.
9. In a machine for placing tuft yarns in carpet manufacture through the tubes of a tube frame the combination of a series of tufting tubes, a cooperating series of needles, a sliding guide bar 76 for the needles, slide rods 77 supporting said bar for movement with the advancing needles but permitting subsequent relative movement between them, and means for halting the forward movement of said guide bar at a point adjacent but to the rear of the tufting tubes while permitting the needles to continue to advance, thereby preventing injury to the tubes by contact of said guide bar therewith.
10. In a machine for placing tuft yarns in carpet manufacture through the tubes of a tube frame for wide work, the combination of a tube frame of a length to support a plurality of spools adapted to be placed successively in said frame after their yarns have been drawn through the corresponding tubes, a series of needles cooperating therewith, and an elongated guide bar for said needles and adapted to advance with them to a position adjacent the tubes of said frame, said guide bar having recesses at its ends whereby said bar may overlie without disturbing the yarn of an adjacent spool already drawn by a previous threading operation when said guide bar comes into close proximity to said tufting tubes.
11. In a machine for placing tuft yarns in carpet manufacture through the tubes of a tube frame, in combination, a series of tufting tubes, a grooved guide bar to guide and align the needles after emerging from the tubes to engage the yarn and guides upon the machine frame in which said guide bar is adapted to be moved in a direction transverse to the movement of the needles and in a straight path, whereby the grooved face of said guide bar is presented simultaneously to the needles over its entire extent.
12. In a machine for placing tuft yarns in carpet manufacture through the tubes of a tube frame, in combination, a series of tufting tubes having large and small ends, a guide bar 82 to guide and align the needles after emerging from the large ends of said tufting tubes, and guiding means 83 on each side of said bar in which said guiding bar 82 is adapted to slide, and means manually to adjust said guiding means accurately to position said bar longitudinally of the machine.
13. In a machine for placing tuft yarns in carpet manufacture through the tubes of a tube frame, the combination of the tufting tubes, the cooperating needles, a guide bar 82 to engage the needles as they emerge beyond the tufting tubes, a comb holder 107 above and adjacent the outer ends of the tufting tubes, said holder adapted to support the yarns in position to be drawn through the tubes, said guide bar having a forward extension underlying said comb holder whereby the needles are positively guided for substantially the entire distance between the tubes and the yarns to be drawn.
14. In a machine for placing tuft yarns in carpet manufacture through the tubes of a tube frame, the combination of a series of tufting tubes, a cooperating series of needles, a movable, notched, guide bar 82 to engage the needles upon emerging from the tufting tubes, a movable knife bar, and operative connections from the knife bar to said guide bar 82 to move the latter periodically.
15. In a machine for placing tuft yarns in carpet manufacture through the tubes of a tube frame, in combination, a series of tufting tubes, a cooperating series of needles, a notched guide bar 82 adapted to engage with the needles as the latter emerge from the tubes, a movable knife bar 89, cam levers 86 adapted to be engaged and moved by said knife bar, and connections from said cam

levers to the guide bar, whereby the latter is depressed by movement of the knife bar.

16. In a machine for placing tuft yarns in carpet manufacture through the tubes of a tube frame, the combination of a series of tufting tubes, a series of cooperating needles, a notched guide bar 82 for the needles, means for periodically bringing the said bar into engagement with the needles, and means for manually adjusting the guide bar longitudinally, said means including blocks 91 having slots 92 for the reception of bolts.

17. In a machine for placing tuft yarns in carpet manufacture through the tubes of a tube frame, the combination of a series of tufting tubes, a cooperating series of needles, and means for yieldingly mounting one or more needles adjacent each end of the series.

18. In a machine for placing tuft yarns in carpet manufacture through the tubes of a tube frame, the combination of a series of tufting tubes, a cooperating series of needles, and means for yieldingly mounting the end needle of said series.

19. In a machine for placing tuft yarns in carpet manufacture through the tubes of a tube frame, the combination of a series of tufting tubes, a cooperating series of needles, and means for yieldingly mounting the end needles of said series, said means including spring 93 normally holding said end needles in position.

20. In a machine for placing tuft yarns in carpet manufacture through the tubes of a tube frame the combination of means upon the machine to support a spool, a comb to engage the yarns upon said spool, a transversely adjustable grooved holder bar for said comb, means to support a tube frame, a series of needles having an advanced and a retracted position and means for shifting said holder bar longitudinally thereof to lay the yarns across the advanced needles, said shifting means including a member adjustable in the direction of movement of the needles to accommodate said shifting means to various positions of adjustment of said holder bar whereby said bar and its shifting means are adapted to cooperate with differently proportioned tube frames.

21. In a machine for placing tuft yarns in carpet manufacture through the tubes of a tube frame the combination of a spool support, a comb, a comb holder therefor, means for moving said comb holder lengthwise of the spool, said means including a vertically pivoted lever arm engaging one end of said holder and means for rocking said arm about its pivot periodically.

22. In a machine for placing tuft yarns in carpet manufacture through the tubes of a tube frame, means at each side of the machine for supporting the opposite ends of spools of normal length thereby to position

said spools for the drawing in of their yarns, 65 said means at one side of the machine also adapted to receive alternatively one end of a shorter spool, and intermediate means for receiving the other end of such shorter spool, said intermediate means being constructed and arranged to be rendered inoperative when desired to permit the positioning and drawing in of the yarns of normal length spools.

23. In a machine for placing tuft yarns in carpet manufacture through the tubes of a tube frame, the combination of a spool support, a comb, a clamp holder 107 therefor, and means for moving said clamp holder lengthwise the spool, said means including a lever having an arm engaging said clamp holder, and a cam engaging said lever periodically to rock the same.

24. In a machine for placing tuft yarns in carpet manufacture through the tubes of a tube frame, the combination of a spool support, a comb, a clamp holder 107 therefor, and means for moving said clamp holder lengthwise the spool, said means including a lever 121 having an adjustable arm 127 engaging the clamp holder, cam 120 engaging said lever and means to rotate said cam.

25. In a machine for placing tuft yarns in carpet manufacture through the tubes of a tube frame, means for rotatably supporting the opposite ends of a spool, spool holding and releasing pawl and ratchet mechanism carried by said means at one end of the spool, and a cam operated rock lever for releasing said mechanism periodically to provide slack in the threads of the spool, thereby to permit the strands to be drawn through the tufting tubes.

26. In a machine for placing tuft yarns in carpet manufacture through the tubes of a tube frame, the combination of tufting tubes, a series of cooperating needles, a spool support, reversible mechanism at one end of the spool to hold the latter against rotation in said support in one or the opposite direction selectively and means to release said mechanism to provide slack in the threads or yarns to permit them to be drawn through the tubes by the retraction of the needles.

27. In a machine for placing tuft yarns in carpet manufacture through the tubes of a tube frame, the combination of a series of tufting tubes, a cooperating series of needles, a spool support, and holding and releasing means for the spool to hold the same or to permit it to rotate to provide slack, the said means including a ratchet, a pawl normally engaging therewith, and means periodically to lift the pawl from engagement with the ratchet, said pawl having a reversible member whereby the pawl is adapted to hold in one or the opposite direc-

- tion accordingly as the spool is positioned in its support with its yarns wound over or under respectively.
28. In a machine for placing tuft yarns in carpet manufacture through the tubes of a tube frame, the combination of a series of tufting tubes, a cooperating series of needles, a spool support and releasing means for the spool to provide slack, said means including a ratchet, a pawl adapted to engage the same, a rotatable cam and operative connections between the cam and the pawl so as periodically to disengage the latter from the ratchet, the portion of said cam effective to disengage the pawl being adjustable to vary the duration of said disengagement. 5
29. In a machine for placing tuft yarns in carpet manufacture through the tubes of a tube frame, the combination of a series of tufting tubes, a cooperating series of needles, a spool support and releasing means for the spool to provide slack, said means including a spool holder, a ratchet thereon, a pawl adapted to engage said ratchet, a rotatable cam having two parts relatively adjustable circumferentially to vary the effective period thereof, and operative connections between the cam and the pawl to lift the latter periodically. 10
30. In a machine for placing tuft yarns in carpet manufacture through the tubes of a tube frame, a series of tufting tubes, a cooperating series of needles, shearing means for cutting the drawn in yarns adjacent the ends of said tubes, said means including a fixed knife, a reciprocable knife, the latter having also a twisting or shearing movement relative to said fixed knife, and means for automatically operating the reciprocable knife. 15
31. In a machine for placing tuft yarns in carpet manufacture through the tubes of a tube frame, a frame having a series of tufting tubes, a support on the machine for said frame, a cooperating series of needles, and means for cutting the drawn in yarns adjacent the ends of said tubes, said means including a fixed knife upon said frame support, and a vertically movable knife cooperating therewith, said vertically movable knife having also a turning movement about a longitudinal axis. 20
32. In a machine for placing tuft yarns in carpet manufacture through the tubes of a tube frame, a frame having a series of tufting tubes, a support on the machine for said frame, a cooperating series of needles, and means for cutting the drawn in yarns adjacent the ends of said tubes, said means including a lower fixed knife, an upper vertically movable knife cooperating therewith, said upper knife adapted also to be turned about an axis extending longitudinally thereof, and means to turn said knife during the shearing operation. 25
33. In a machine for placing tuft yarns in carpet manufacture through the tubes of a tube frame, a series of tufting tubes, a cooperating series of needles, and means for cutting the drawn in yarns adjacent the ends of said tubes, said means including a knife fixed relation to the tubes and drawn in yarn ends and a cooperating reciprocable knife having also a yielding movement relative to said fixed knife. 30
34. In a machine for placing tuft yarns in carpet manufacture through the tubes of a tube frame, a series of tufting tubes, a cooperating series of needles, and means for cutting the drawn in yarns adjacent the ends of said tubes, said means including a lower fixed knife, an upper knife the edge of which when raised overlies the lower knife, a cam member connected to the movable knife, said cam member having a lower bevelled edge and cooperating means to twist said upper knife when reciprocated to shear the yarn ends. 35
35. In a machine for placing tuft yarns in carpet manufacture through the tubes of a tube frame, a series of tufting tubes, a cooperating series of needles, and means for cutting the drawn in yarn adjacent the ends of said tubes, said means including a lower fixed knife, an upper movable knife, and supporting means for the latter, whereby the movable knife when elevated lies over the stationary knife, and whereby as the movable knife is depressed, it is yieldingly forced laterally against the fixed knife. 40
36. In a machine for placing tuft yarns in carpet manufacture through the tubes of a tube frame, a series of tufting tubes, a cooperating series of needles, and means for cutting the drawn in yarn adjacent the ends of said tubes, said means including a lower fixed knife, an upper movable knife, a cam member 140 connected to the movable knife, a pivot 141 for the movable knife, and a spring 142 for holding said movable knife normally in forward position but permitting it to swing yieldingly upon said pivot. 45
37. In a machine for placing tuft yarns in carpet manufacture through the tubes of a tube frame, a series of tufting tubes, a cooperating series of needles, and means for cutting the drawn in yarn adjacent the ends of said tubes, said means including a lower fixed knife, an upper movable knife, a transverse supporting beam 89 for the movable knife, pivotal means for said beam and vertically reciprocable plunger rods for operating said supporting beam. 50
38. In a machine for placing tuft yarns in carpet manufacture through the tubes of a tube frame, a series of tufting tubes, a cooperating series of needles, and means for cutting the drawn in yarn adjacent the ends of said tubes, said means including a lower fixed knife, an upper reciprocable knife, a 55

supporting member therefor, said member being yieldingly movable about a longitudinal axis, means normally tending to move said member to press said reciprocable knife 5 toward said fixed knife, a stop limiting such movement, and means to reciprocate said member and its knife.

39. In a machine for placing tuft yarns in carpet manufacture through the tubes of a 10 tube frame, a set of tufting tubes, a cooperating set of needles, shearing means including fixed and movable knives to sever the strands in proximity to said tubes, and means for clamping the yarn strands against 15 said fixed knife during the yarn severing operation, said clamping means including a holding bar extending lengthwise the machine and connections therefrom to the shearing mechanism, so that when the needles are advanced, the holding bar is elevated out of the way.

40. In a machine for placing tuft yarns in carpet manufacture through the tubes of a tube frame, a set of tufting tubes, a cooperating set of needles, shearing means including fixed and movable knives to sever the yarn ends in proximity to said tubes, and means for clamping said yarns against 25 said fixed knife during the severing operation.

41. In a machine for placing tuft yarns in carpet manufacture through the tubes of a tube frame, a set of tapered tufting tubes, a cooperating set of needles, shearing means 35 to sever the strands in proximity to said tubes, said means including a reciprocable knife member and a support therefor yieldable about a longitudinal axis, and means for clamping the yarn strands between the 40 small ends of the tufting tubes and the shearing means, said clamping means including a holding bar, vertically movable plunger pins therefor, coil springs surrounding said pins, and guide members for said 45 plunger pins upon said support for said reciprocable knife member and against which guide member said springs are adapted to be compressed.

42. In a machine for placing tuft yarns 50 in carpet manufacture through the tubes of a tube frame, a set of tapered tufting tubes, a cooperating set of needles, shearing means to sever the strands in proximity to said tubes, and including fixed and movable knives and means for clamping the 55 yarn strands between the small ends of the tufting tubes and the shearing means and against said fixed knife, said clamping means including a holding bar 152, plunger 60 pins 153 extending upwardly therefrom, coil springs 154 surrounding said plunger pins, and a overhead support against which the coil springs are adapted to be compressed.

43. In a machine for placing tuft yarns in

carpet manufacture through the tubes of a tube frame, a set of tapered tufting tubes, a cooperating set of needles, shearing means including fixed and movable members to sever the strands in proximity to said tubes, and means for clamping the yarn strands against said fixed shearing member between the small ends of the tufting tubes and the shearing means, said clamping means including a holding bar 152, plunger pins and coil springs cooperating therewith and movement limiting means carried by each pin. 70

44. In a machine for placing tuft yarns in carpet manufacture through the tubes 80 of a tube frame, the combination of a comb having teeth adapted to receive and retain yarn ends and to prevent the same from becoming disengaged by movement longitudinally of the teeth and a comb holder therefor said holder provided with means for receiving and supporting said comb with its teeth foremost or the reverse. 85

45. In a machine for placing tuft yarns in carpet manufacture through the tubes of a tube frame the combination of a spool support for a spool in one position or in a position reversed end for end therefrom, a cooperating comb for holding the yarn ends, said comb having a toothed edge and a turned over edge, and a comb holder upon the machine for receiving and supporting said comb with either edge foremost. 90

46. In a machine for placing tuft yarns in carpet manufacture through the tubes of a tube frame the combination of a spool support for receiving a spool with the yarn ends wound under or wound over, a cooperating comb for holding the yarn ends, said comb having a toothed edge and a straight 100 edge, and means upon the machine to support said comb with either edge foremost according to the position of the spool in its support. 95

47. In a machine for placing tuft yarns in carpet manufacture through the tubes of a tube frame, the combination of a spool support, a cooperating yarn clamp, a holder for the yarn clamp, said clamp having teeth and the holder being constructed to permit the clamp to be inserted to a depth leaving enough of the teeth outside the clamp holder to permit the yarn strands to withdraw readily from the clamp without binding against the holder. 110

48. In a machine for placing tuft yarns in carpet manufacture through the tubes of a tube frame, the combination of a spool support, a toothed yarn clamp, a holder therefor having means to receive and support said clamp with teeth foremost or the reverse, and means to manipulate the holder to permit ready insertion of the clamp in either of said positions. 115

49. In a machine for placing tuft yarns 120

- in carpet manufacture through the tubes of a tube frame the combination of a spool support, a toothed yarn clamp, a holder therefor having means to receive and support said clamp with teeth foremost or the reverse, and means to insure the proper longitudinal position of said clamp in its holder in either of said positions and with the teeth in proper alignment.
- 5 50. In a machine for placing tuft yarns in carpet manufacture through the tubes of a tube frame, the combination of a spool support, a clamp for the yarn ends, a holder for the clamp, and means to manipulate the holder for the reception and holding of the clamp, said means including a sliding bar 162.
- 10 51. In a machine for placing tuft yarns in carpet manufacture through the tubes of a tube frame, in combination, a spool support, means for holding the yarn ends in separated relation for threading, and supplemental yarn separating means for the end yarns of a spool.
- 15 52. In a machine for placing tuft yarns in carpet manufacture through the tubes of a tube frame, in combination, a spool support, means for holding the yarn ends in separated relation for threading, and supplemental yarn separating means for the end yarns of a spool, said supplemental means being supported upon the machine for movement into functioning or non-functioning position.
- 20 53. In a machine for placing tuft yarns in carpet manufacture through the tubes of a tube frame, in combination, a spool support, a comb for holding the yarn ends in separated relation for threading, a supplemental comb for separating the end yarns of the spool, and means for mounting said supplemental comb upon the machine to permit it to be moved into functioning position in proximity to the yarn ends or to be removed therefrom.
- 25 54. In a machine for placing tuft yarns in carpet manufacture through the tubes of a tube frame, in combination, a spool support, tufting tubes, a set of cooperating needles, a comb, a supplemental comb 167 and means for holding said supplemental comb in various adjusted positions relative to said needles.
- 30 55. In a machine for placing tuft yarns in carpet manufacture through the tubes of a tube frame, the combination of a spool support, a comb for holding the yarn ends in separated relation for threading, a supplemental comb for separating the end yarns of the spool and means for yieldingly mounting said supplemental comb upon the machine.
- 35 56. In a machine for placing tuft yarns in carpet manufacture through the tubes of a tube frame, a spool support, tufting tubes,
- a set of cooperating needles, a yarn carrying spool in said support, means to move said needles to and fro, and means automatically to turn said spool to tighten the yarns or threads upon the spool support to prevent 70 improper engagement of said yarns or threads and the advancing needles.
- 40 57. In a machine for placing tuft yarns in carpet manufacture through the tubes of a tube frame, a spool support, tufting tubes, 75 a set of cooperating needles, means to move said needles to and fro, means to hold the yarns in spaced relation to permit the needles to pass between them, and means momentarily additionally to tighten the 80 yarns or threads as the needles approach the same in their forward movement.
- 45 58. In a machine for placing tuft yarns in carpet manufacture through the tubes of a tube frame, a spool support, tufting tubes, a 85 set of cooperating needles, means to move said needles forwardly between the yarn ends and to retract the needles, means momentarily to tighten the yarns or threads upon the spool support as the needles move forwardly to 90 prevent improper engagement of the needles with said yarns or threads, and means to release said tightening means.
- 50 59. In a machine for placing tuft yarns in carpet manufacture through the tubes of a tube frame, the combination of a spool support, tufting tubes, a set of cooperating needles, means to move said needles forwardly between the yarn ends and to retract the needles and means positively to turn the 100 spool in said support thereby to tighten the yarns as the needles approach the same.
- 55 60. In a machine for placing tuft yarns in carpet manufacture through the tubes of a tube frame, the combination of a spool support, tufting tubes, a set of cooperating needles, means to move said needles forwardly between the yarn ends and to retract the needles, means positively to turn the 105 spool in said support thereby to tighten the 110 yarns as the needles approach the same, and means to release said tightening means prior to retraction of the needles.
- 60 61. In a machine for placing tuft yarns in carpet manufacture through the tubes of a tube frame, the combination of a spool support, tufting tubes, a set of cooperating needles, means to move said needles forwardly between the yarn ends and to retract the needles, means momentarily to tighten the 115 yarns as the needles approach the same in their forward movement, means to hold the 120 yarn ends against unwinding during the first part of the retracting movement of the needles, and means subsequently to release 125 said holding means.
- 65 62. In a machine for placing tuft yarns in carpet manufacture through the tubes of a tube frame, the combination of a spool support, tufting tubes, a set of cooperating 130

needles, means to move said needles forwardly between the yarn ends and to retract the needles, means to tighten the yarns or threads as the needles approach the same 5 in their forward movement, means subsequently to release said tightening means, and other spool holding and releasing mechanism for holding the spool during a portion of the retracting movement of the needles, 10 and means to release said holding mechanism to provide slack in the yarns or threads to permit them to be drawn through the tubes by the retraction of the needles.

63. In a machine for placing tuft yarns 15 in carpet manufacture through the tubes of a tube frame for wide work the combination of a tube frame having means to support for rotation as a unit a plurality of aligned spools, a spool support upon the machine, a 20 series of needles for engaging the yarns of a spool in said support upon the machine and drawing them through the tubes of the frame, severing mechanism for the drawn in yarn ends, means automatically to stop 25 the machine after the drawing in of said yarns but before severing of the yarn ends, thereby to permit the spool to be withdrawn from the holder upon the machine and placed in the spool supporting means upon 30 the tube frame prior to severing of the drawn in yarn ends, and means for operating said severing mechanism upon subsequent starting of the machine.

64. In a machine for placing tuft yarns in 35 carpet manufacture through the tubes of a tube frame for wide work, the combination of a tube frame having means to support a plurality of aligned and interlocked spools, a spool support upon the machine, a series 40 of needles for engaging the yarns of a spool in said support upon the machine and drawing them through the tubes of the frame, severing mechanism for the drawn in yarn ends, means automatically to stop the machine after the drawing in of said yarns but before disengagement of the needles therefrom and before severing of the yarn ends, thereby to permit the spool to be withdrawn from the holder on the machine 45 50 and placed in the spool supporting means upon the tube frame prior to severing of the drawn in yarn ends, means to hold each spool against turning when so positioned on the frame, and means operable upon subsequent starting of the machine for fully 55 disengaging the needles from the yarns and for operating said severing mechanism, thereby obviating the necessity for additional trimming of the yarn ends after the 60 yarns of all the spools have been drawn in.

65. In a machine for placing tuft yarns

in carpet manufacture through the tubes of a tube frame for wide work, the combination of a tube frame having means to support a plurality of aligned and interlocked spools, a spool support upon the machine, a series of needles for engaging the yarns of a spool in said support on the machine and drawing them through the tubes of the frame, severing mechanism for the drawn in yarn ends, means automatically to stop the machine after the drawing in of said yarns but before severing of the yarn ends, thereby to permit the spool to be withdrawn from the holder on 65 the machine and placed in the spool supporting means upon the tube frame prior to severing of the drawn in yarn ends, means to hold each spool against turning when so positioned on the frame, and means for operating said severing mechanism upon subsequent starting of the machine whereby when the frame has been filled the yarn ends of all the interlocked spools thereon project a uniform length beyond the tubes and re- 70 75 80 85 quire no further trimming.

66. That method of placing the tuft yarns in carpet manufacture through the tubes of a tube frame adapted to support a plurality of aligned spools for rotation as a unit 90 which consists in drawing the yarns through a section of tubes of the frame, in placing the spool carrying said yarns in the tube frame before severing of the yarn ends, in clamping said spool against turning, in subsequently 95 severing the drawn in yarn ends while the spool is supported in the frame and in repeating said steps for each section of tubes until all the tubes have been threaded whereby the yarn ends for all the tubes of the 100 frame will have a uniform length without subsequent trimming.

67. That method of placing the tuft yarns in carpet manufacture through the tubes of a tube frame adapted to support a plurality 105 of aligned spools for rotation as a unit which consists in drawing the yarns through a section of tubes of the frame, in placing the spool carrying said yarns in the tube frame before severing of the yarn ends, in 110 subsequently severing the drawn in yarn ends while the spool is supported in the frame and in repeating said steps for each section of tubes until all the tubes have been threaded whereby the necessity for subsequent trimming of the yarn ends to give them a uniform length as required for use in a loom is obviated.

In testimony whereof, we have signed our names to this specification.

EDGAR F. HATHAWAY.
WALTER BIXBY.
